UNITED STATES PATENT OFFICE

2,561,595

GAS TANK HOLDER

Robert B. Putnam, Minneapolis, Minn., assignor
to Jay A. Andersen, Minneapolis, Minn.

Application May 4, 1946, Serial No. 667,449

14 Claims. (Cl. 211—75)

1 This invention relates to a tank-holding device and while the invention might have various applications, it is illustrated as applied to a device for holding cylindrical tanks holding compressed gas. Such gas is commonly referred to as "bottled gas." Said gas is used for fuel in domestic establishments and for other purposes. The tanks held have valve mechanism at their upper ends which are connected to a regulator carried by the device.

It is an object of this invention to provide a simple and efficient structure for receiving and supporting said tanks and regulating equipment, holding them in the proper position off of the ground and having a cover at its top movable over the tops of said tanks and equipment and adapted to be locked in such position to prevent any one tampering with said tanks and equipment.

It is a further object of the invention to provide a tank-holding device comprising a base having spaced portions adapted to receive and support the lower ends of cylindrical or other shaped tanks, a standard extending vertically from said base and a housing hinged to the upper end of said standard and adapted to swing to forward position over the tops of said tanks or to rearward position exposing the tops of said tanks.

It is another object of the invention to provide such a device as set forth in the preceding paragraph, together with a front standard extending vertically from said base and a member secured to and extending between said front and rear standards and disposed between said tanks adjacent the tops thereof.

It is still further an object of the invention to provide such a device as set forth in the preceding paragraph save one, together with a bracket secured to said rear standard intermediate the ends thereof and extending rearwardly therefrom, said bracket having means adapted to engage and be secured to a wall.

It is more specifically an object of the invention to provide a tank-holding device comprising a base having laterally spaced substantially cylindrical portions for receiving and supporting the lower ends of gas tanks, a third member disposed between and secured to said portions and having front and rear sides, a rear standard secured to the rear side of said third member and extending vertically therefrom and being preferably of tough or channel shape upon which provision is made for mounting a regulator, a front standard secured to the front side of said third member and extending vertically therefrom, a

2 member similar to said third member secured to and extending between said front and rear standards adjacent the upper ends of said tanks and disposed between said tanks; a housing hinged to the upper end of said rear standard and adapted to swing to forward position over the tops of said tanks to protect the same from tampering and to rearward position exposing the tops of said tanks.

10 These and other objects and advantages of the invention will be fully set forth in the following description made in connection with the accompanying drawings in which like reference characters refer to similar parts throughout the several views and in which:

Fig. 1 is a view in front elevation of the device, the tanks to be held being shown in dotted lines;

Fig. 2 is a top plan view of the device;

Fig. 3 is a horizontal section taken on line 3—3 of Fig. 1, as indicated by the arrows;

Fig. 4 is a view in side elevation of the device;

Fig. 5 is a partial vertical section taken substantially on line 5—5 of Fig. 2, as indicated by the arrows;

Fig. 6 is a partial vertical section taken on line 6—6 of Fig. 3, as indicated by the arrows;

Fig. 7 is a partial vertical section taken substantially on line 7—7 of Fig. 8, as indicated by the arrows;

Fig. 8 is a partial vertical section taken on line 8—8 of Fig. 7, as indicated by the arrows;

Fig. 9 is a view partly in front elevation and partly in vertical section showing regulating equipment;

Fig. 10 is a vertical section on line 10—10 of Fig. 9, showing said equipment; and

Fig. 11 is a horizontal section on line 11—11 of Fig. 10.

Referring to the drawings, a device is shown 40 comprising a base 10, said base having laterally spaced portions 10a which are secured to a third member 10i disposed therebetween. While portions 10a could be varied in form, in the embodiment of the invention illustrated each comprises an outer cylindrical flange 10c having a terminal outwardly extending supporting peripheral flange 10d. Each portion 10a also has an inner substantially cylindrical flange 10e which flares upwardly and has an inwardly extending supporting peripheral flange 10f. Flanges 10c and 10e are connected at their tops by a channel-shaped portion or bead 10g and a horizontally extending portion 10h. Ribs 10k may be pressed upwardly along portions 10h and 10g, as shown 45 in Figs. 3 and 6, to provide strength and act as

drain channels. Each portion 10a thus forms an annular channel with its open side directed downwardly. Disposed between portions 10a is the third member 12, the same having sides extending about flanges 10c engaging the same and secured thereto by rivets or screws 10j. Member 12 has a front side which is curved in concave form and a rear side having a central portion extending substantially parallel to a line connecting the centers of portions 10a and side portions converging toward said rear side. As shown in Figs. 7 and 8, member 12 has a top platelike portion and downwardly extending peripheral flanges. Portions 10a and member 12 can be pressed from sheet metal. A rear standard 11 fits about the rear side of member 12, the same thus being of channel or trough shape with flaring sides, and the same extends vertically from member 12 and is secured thereto by rivets or screws 11a. Another member 13 is disposed some distance above base 10 and adjacent the tops of the tanks 14 supported in the device. Member 13 is identical in form with member 12 so that standard 11 fits about the same at its rear side and is secured thereto by rivets or screws 15. Member 13 has a rather large aperture 13a therethrough to accommodate regulator connections. A front standard 17 of segmental form in transverse cross section fits against the front side of member 12 and is secured thereto by rivets or screws 18. Front standard 17 therefore has its front side of concave form and extends vertically to and fits against the front side of member 13, being secured thereto by rivets or screws 19. Standard 17 has a forwardly projecting top and bottom horizontal flange 17a through the top one of which extends a hole 17b. Rear standard 11 extends above member 13 and its rear side curves forwardly and terminates in a plane vertical flange 11a. Holes 11e extend through standard 11 to accommodate attaching bolts for a regulator 35. A housing 20 is provided having a top portion which is curved in substantially semi-cylindrical form at its front portion and extends rearwardly in a plane portion, said latter portion having a vertically extending rear part 20a. A hinge 21 has one butt secured to the underside of the top of housing 20 adjacent portion 20a and has its other butt bent at right angles and extending along the front side of flange 11a to which it is secured by rivets or screws 22. Hinge 21 will be secured to housing 20 in any suitable manner, as by welding. Portion 20a is provided with a central recess 20b to accommodate the upper end of standard 11. Housing 20 has a vertically extending front side 20c and vertically extending side portions 20d, said portions 20c and 20d merging in curved form with the curved top of said housing. The lower edge portions of portions 20a and 20d are curved outwardly slightly to allow for draining of water and moisture. The front side 20c extends downwardly and has a horizontal flange 20e extending forwardly therefrom and having a short downwardly extending terminal portion, said flange 20e being adapted to a position adjacent but spaced vertically from flange 11a and having an aperture 20f therein aligning with hole 17b. Aligned holes 17b and 20f are adapted to receive a lock such as a padlock 24. It will be seen that housing 20 can swing to its forward position shown in Figs. 1, 4 and 5, and also to a rearward position, shown in dotted lines in Fig. 4. A supporting prop or bracket 36 is secured in any suitable manner, as by rivets

37, to the upper end of standard 11, the same projecting upwardly and forwardly. A small clip or angle bracket 38 is secured to the inner surface of housing 20 in any suitable manner, as by welding, and when housing 20 is in its lower position with no tanks 14 present, bracket 38 will engage bracket 36 and support the housing 20. When tanks 14 are in position, housing 20 is supported by its lower edge engaging the tops of said tanks, as shown in the drawings. Rear standard 11 at its lower end is provided with a plurality of louvers 11d. Bracing members 25 and 26, which may be identical, are secured in laterally spaced relation to the rear side of standard 11 at the inner side thereof, and member 25 extends upwardly and is secured to the rear side of front standard 17 substantially centrally thereof by rivets or screws 27. Member 26 extends downwardly and is secured to the rear side of front standard 17 substantially centrally thereof by rivets or screws 28. Members 25 and 26 are secured to rear standard 11 by rivets or screws 29. Braces 25 and 26 thus provide both diagonal and torque bracing. 25 A bracket 30 of channel form has its central portion engaging the outer side of standard 11 and secured thereto by rivets or screws 31. The sides of bracket 30 have terminal flanges extending outwardly therefrom which are adapted to engage and be secured to a wall 32 by bolts 33. Holes 11c are provided in standard 11 so that bracket 30 can be secured in various positions. In Figs. 9 and 10 the regulating and dispensing equipment is shown. This comprises the regulator 35 which has a top connection 35a which will be connected by a short nipple 39 to a three-way cock 40 having a handle 41 connected thereto. Regulator 35 is secured by screws 35b passing through slots 11e. Cock 40 is connected at either side by suitable connections 42 to tubes 43 which extend respectively to valves 44 which are secured by nipples 45 to the tanks 14. Valves 44 are provided with suitable handles 44a. The passage of gas from tanks 14 can be regulated by manipulating valve handles 44a. An outlet 46 is connected to regulator 35. In operation the device will be disposed in a desired location and if it is adjacent a wall, bracket 30 may be connected to said wall, as described. With housing 20 in its raised or rearward position, the tanks can conveniently be placed on the base comprising portions 10a and will be centered therein and supported therein firmly in position. The connections will be made to the tanks, as described and shown in Figs. 9 and 10, and the gas will be dispensed in the usual manner by manipulation of valves 44 and cock 40. The gas passes through the regulator 35 and will be conveyed through outlet conduit 46 to the desired location. It will be seen that opening 13a will accommodate movement of handle 41. A plurality of the holes or slots 11e will be provided so that any type of standard regulator can be easily and quickly attached to standard 11. With housing 20 in its upper or rearward position complete access can be had to the tanks and regulating equipment. When the tanks are unattended, the housing 20 can be swung down to its forward position, in which it engages and effectively encloses the upper ends of the tanks and the valve and regulator mechanism. At this time flange 20e is located adjacent the flange 11a and holes 17b and 20f are in vertical alignment and the lock 24 can be placed therethrough so that housing 20 will be

locked in position. The valves at the tops of the tanks and the dispensing and regulating equipment are now completely covered and protected and access cannot be had thereto so that any tampering with the tanks, valves or regulating equipment is prevented. It will be noted that hinge 21 is disposed at the inner side of housing 20 and standard 11 where it is always covered and protected from the weather and where it cannot be tampered with when the housing 20 is locked in its forward or lower position. The louvres 11d will provide some circulation in the rear of tanks 14 and the front of standard 11.

From the above description it will be seen that I have provided a comparatively simple and yet efficient gas tank holder. The same is very efficiently constructed for carrying and protecting the dispensing and regulating mechanism for the gas. When the housing is in its forward or lower position and locked in place, the upper ends of the tanks, together with the regulating valves, the dispensing and regulating equipment are completely protected against tampering by any unauthorized person. All parts of the device can be pressed from sheet metal and the structure is very strong and rugged for the use to which it will be put. It will be noted that front column 17 is symmetrical about central vertical and horizontal axes and can thus be reversed end for end in assembly. The device can be easily and readily fabricated and can thus be produced at a reasonable price. The device has been amply demonstrated in actual practice, found to be very successful and efficient and is being commercially made.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A device of the class described having in combination, a base member having portions with recesses adapted to receive the lower ends respectively of cylindrical tanks, said base having a second member connecting said portions, a standard extending vertically from the rear portion of said second member and adapted to be disposed in the rear of said tanks, a second standard extending upwardly from the front portion of said second member, a member secured to said standards adjacent the tops thereof and adapted to be disposed between said tanks, and a housing hinged to said first mentioned standard adjacent the top thereof arranged to swing rearwardly to expose said tanks and adapted to move to forward position disposed over the tops of said tanks, the same having a portion adjacent the top of said second standard when disposed in said forward position.

2. A device of the class described having in combination, a supporting base member having laterally spaced portions with recesses adapted to receive the lower ends of cylindrical tanks, a second member extending between and connecting said portion, a standard extending vertically from the rear side of said second member, a second standard extending vertically from the front of said second member, a third member extending between said standards adjacent the tops thereof and adapted to be disposed between said tanks, a housing hinged to said first mentioned

standard adjacent its top and adapted to be moved to position to extend over the tops of said tanks and having a portion adjacent the top of said second standard when so moved, and means for locking said housing to the top of said second standard when in said position.

3. The structure set forth in claim 2, and a bracket adapted to be secured to said first mentioned standard at various points thereon, extending rearwardly therefrom and adapted to be connected to a wall.

4. A device of the class described having in combination, a supporting base member having laterally spaced portions adapted to support respectively the lower ends of spaced cylindrical tanks, a second member connecting said portions, a standard secured to the rear of said second member substantially centrally thereof and extending vertically therefrom, a front standard secured to the front portion of said second member substantially centrally thereof and extending vertically therefrom, a member connecting said standards adjacent the upper ends thereof and adapted to be disposed between said tanks, and a housing hinged at its rear side to said first mentioned standard and adapted to be moved to position over the tops of said tanks, and means at the front of said housing for locking the same in position.

5. A device of the class described having in combination, a supporting base member having laterally spaced portions adapted to support respectively the lower ends of cylindrical tanks, a second member having concave sides connecting said portions adapted to accommodate said spaced portions, a standard secured to the rear of said second member substantially centrally thereof and extending vertically therefrom, a front standard secured to the front portion of said second member substantially centrally thereof and extending vertically therefrom, a member connecting said standards adjacent the upper ends thereof and adapted to be disposed between said tanks and having concave sides adapted to accommodate said tanks, and a housing hinged at its rear side to said first mentioned standard and adapted to be moved to position over the tops of said tanks, said first mentioned standard having considerable width, a member secured to said first mentioned standard substantially midway of its height and extending downwardly to said front standard, and another member secured to said first mentioned standard substantially midway of its height and extending upwardly to said front standard.

6. A device of the class described having in combination, a base having laterally spaced portions adapted to receive, surround and support respectively the lower ends of spaced cylindrical tanks, a member disposed between said portions, extending partly around and secured to said portions and having front and rear sides, a rear standard secured to said rear side and extending vertically therefrom, a front standard secured to said front side and extending vertically therefrom, a second member disposed adjacent the tops of said tanks shaped similarly to said first mentioned member and secured to said standards, said rear standard extending above said last mentioned member, a housing hinged to said rear standard and adapted to swing to forward position over the tops of said tanks and having a front portion disposed closely adjacent said second member with said housing in said forward position.

7. The structure set forth in claim 6, said front side being concavely curved and said front standard being of segmental form in transverse across section and having a concave front side.

8. The structure set forth in claim 6, said rear side being of substantially trapezoidal form and said rear standard being of trapezoidal trough shape in cross section and fitting about said rear side.

9. A device of the class described having in combination, a supporting base having laterally spaced portions each having an outer cylindrical supporting flange and an inner substantially cylindrical flange having portions flaring upwardly at its inner edge, said inner flanges being adapted to receive and support the lower ends of spaced cylindrical tanks, a member disposed between said first mentioned portions and having curved sides extending about said outer flanges respectively and secured thereto, said member having a rear side extending substantially parallel to a line connecting the centers of said first mentioned portions and having sides converging towards said rear side, a rear standard of channel form fitting about said sides of said member and extending vertically therefrom, a second member secured to said rear standard adjacent the tops of said tanks and adapted to be disposed between said tanks, a housing hinged to the upper end of said rear standard and adapted to swing to forward position over the tops of said tanks and to swing to rearward position exposing the tops of said tanks.

10. The structure set forth in claim 9, said first mentioned member having a front side disposed between said outer flanges, a front standard secured to said front side and extending vertically therefrom, means connecting said front standard and said first mentioned member, said front standard having a portion disposed adjacent the front part of said housing and adapted to be locked thereto.

11. A device of the class described having in combination, a base member having laterally spaced portions adapted to support respectively the lower ends of spaced cylindrical tanks, a second member fitting partially about and connecting said portions, a standard secured to the rear side of said second member substantially centrally thereof and extending vertically therefrom, a second standard secured to the front side of said second member and extending vertically therefrom, a third member connecting said standards adjacent the tops thereof and adapted to be disposed between said tanks, and a housing hinged to the upper end of said rear standard, said housing having depending walls the lower edge portions of which are constructed and arranged to fit about the convexly rounded upper surfaces of said tanks.

12. A device of the class described having in combination, a base member having laterally spaced portions adapted to support respectively the lower ends of spaced cylindrical tanks, a second member connecting said portions, a standard secured to the rear of said second member substantially centrally thereof and extending verti-

cally therefrom, a housing adjacent the upper end of said standard, a hinge secured to said standard and housing, whereby said housing can swing to forward position over the tops of said tanks and to rearward position exposing said tanks and means for locking said housing in said forward position, said hinge being disposed at the inner side of said housing and covered thereby so that it is not accessible from the outside of said housing and thus cannot be tampered with when said housing is locked in forward position.

13. A device of the class described having in combination, a base adapted to rest on a supporting surface and having spaced portions with substantially cylindrical flanges adapted to receive and support the lower ends of spaced gas-containing tanks, a member fitting about and connecting said portions, front and rear standards extending vertically from and secured to the front and rear sides of said member respectively, a second member similar to said first mentioned member secured to said standards adjacent the tops thereof and adapted to be disposed between said tanks and a housing hinged to the upper end of said rear standard above said tanks and adapted to be swung to forward position over the tops of said tanks or to rearward position exposing the tops of said tanks, said rear standard being of channel form in horizontal cross-section with its open side directed forwardly and having means adjacent its upper end for receiving attaching means for supporting a gas regulator at its inner side, said second member having an opening therethrough for the passage of connections between said regulator and tanks.

14. A device of the class described having in combination, a base having spaced portions having substantially cylindrical flanges and adapted respectively to receive and support the lower ends of gas-containing tanks, a member fitting about and connecting said portions, front and rear standard extending vertically from and secured to said member, a housing hinged to the upper end of said rear standard and adapted to swing to forward position over the tops of said tanks or to rearward position exposing the tops of said tanks, a supporting member secured adjacent the top and at the inner side of said rear standard and projecting upwardly, and a clip secured to the inner side of said housing adapted to engage said supporting member when said housing is in forward position with no tanks in said device.
